L. J. QUINN.
KNITTING MACHINE.
APPLICATION FILED APR. 7, 1915.

1,204,590.

Patented Nov. 14, 1916.

UNITED STATES PATENT OFFICE.

LORAIN J. QUINN, OF BRANTFORD, ONTARIO, CANADA, ASSIGNOR TO SCOTT & WILLIAMS, INCORPORATED, OF CAMDEN, NEW JERSEY, A CORPORATION OF NEW JERSEY.

KNITTING-MACHINE.

1,204,590.

Specification of Letters Patent. Patented Nov. 14, 1916.

Continuation in part of application Serial No. 811,269, filed January 9, 1914. This application filed April 7, 1915. Serial No. 19,840.

To all whom it may concern:

Be it known that I, LORAIN J. QUINN, a citizen of the United States, and resident of Brantford, in the Province of Ontario, Canada, have invented certain new and useful Improvements in Knitting-Machines, of which the following is a specification.

My invention relates to knitting machines for knitting interconnected two-ply plain fabrics.

One object of my invention is to provide a machine having two sets of needles with improved devices for producing simultaneously from two or more knitting yarns plain fabrics knit respectively upon each set of needles, and facing in opposite directions, said fabrics being connected by the inclusion of sinker wales of the fabric of one face in knit wales of the fabric of the other face.

While my invention is capable of being applied to any knitting machine having carriers for two sets of needles drawing loops in opposite directions, I have illustrated it as applied to a cylinder and dial knitting machine.

In the accompanying drawings; Figure 1 is a development in elevation showing the needles of one carrier as for instance the cylinder. Fig. 2 is a plan view above the needle dial of such a machine. Fig. 3 is a view of the inner or dial face of the fabric produced.

As disclosed in my application Serial No. 811,269 filed January 9, 1914, of which this application is a continuation in part, fabrics of the type desired to be produced may be formed by feeding a yarn such as the yarn α to a primary set of needles, here shown for example only as the dial needles 1, said needles being actuated to knit with such yarn α only, all of the secondary or cylinder needles 2 being positioned to receive the sinker wales between adjacent wales of the dial-needle fabric upon their shanks, and the cylinder needles thereafter being fed with a separate yarn γ , and actuated to knit, whereupon the sinker wale loops of the primary or dial fabric, as well as the face loops of the secondary or cylinder fabric, are cast off upon the new loop of the yarn γ drawn by the secondary or cylinder needles.

Either set of needles may be first to re-

ceive the yarn and knit, as will be obvious, and I hereinafter refer to said set of needles as "primary" needles, and to the subsequently actuated set of needles as "secondary" needles.

I am aware that oppositely facing two-ply connected fabrics have heretofore been formed by the successive operation of two sets of needles, for instance as disclosed in the patent to D. C. Bellis No. 709,734, dated September 23, 1902, a machine having devices for projecting some of the needles of the secondary set to receive tying-loops of the yarn knit by the primary set being disclosed in the patent to said Bellis No. 714,998, dated December 2, 1902.

I have now devised improved means for moving the needles and feeding the yarns whereby the knitting waves for both fabrics are brought into juxtaposition and an increased number of yarn feed points and knitting waves is permitted, the fabrics being connected at each sinker wale of one of said fabrics in the same manner as shown in Fig. 2 of said Patent No. 709,734, at each course, long relative movement between a needle of either set in a projected position and the needle cams being at the same time avoided. My new devices also provide improved means for controlling the operation of the needle-latches.

Referring now to the drawings in which the lines A—A, B—B indicate the same radial planes for cylinder and dial, and assuming the dial fabric to be the primary fabric, I provide the machine with any suitable form of dial needle cams for giving the dial needles an early advance, for instance having an advancing incline as at 20, to clear their latches of their previous loops, followed by a concentric portion 22. Relatively and adjustably fixed in any usual manner with respect to the dial cam-carrier (not shown) which may be of any usual construction, a latch guard and yarn-feed plate 3 provided with a latch guard portion 4 having a beveled end 5 lies above the dial needles projected by the cam incline 20. The position and adjustment of the latch guard 4 is as shown such as to prevent the opened latches of the projected dial needles from closing.

At a point coincident with or outside of

the latch guard 3 I provide a fixed yarn guide 6 for the primary yarn α . This yarn guide may be as shown an adjustable arm having a vertical bore 7, attached on the outer face of latch guard 3, as by the screw 8. The adjustment is such as to bring the yarn bore 7 close to or within the hooks of the projected dial needles now traveling in the concentric portion 22 of their cams. The dial needles having received the yarn are now actuated to knit by a stitch cam 23 provided on the dial cam carrier.

Coincident with, prior to, or following the advance of the dial needles at slope 20 the cylinder needles are advanced, within the inner cylindrical face of latch guard 3 by an advancing slope 30 formed by any suitable combination of cam elements carried by a cylinder cam ring (not shown) of any usual construction. Needles so advanced open their latches, which are held open by the inner face of latch guard 3. The advance given the cylinder needles at this time may be to any desired extent sufficient to clear the ends of their open latches above the plane of the dial needles. Preferably the form given the advancing wave of the cylinder needles is that shown, a second advancing slope 32 completing the elevation 30 of said cylinder needles.

It will be observed that needles moved as by stitch cam 23 will draw the yarn α against the shank of the cylinder needles. This movement is also sufficient to cause the dial needles to penetrate the old loop held upon the shank of the dial needles, the latch closing by contact with the old dial loop.

In order to permit the closing movement of the latches of the dial needles, the latch 40 guard 4 is cut away at 9, the vertical extent of the cut being sufficient to permit the swinging of the dial latches but insufficient to expose the latches of the advanced cylinder needles in the position attained at cam 32. Latch guard plate 3 is thus provided with a portion 12 for guarding the latches of the cylinder needles following that part 45 of the guard effective upon the dial needles, and preceding the feed point for the cylinder needles. The dial needles having now completed stitches having their sinker wales lying upon the shank of the cylinder needles, the dial needles may be paid back as by a cam incline at 24, but this 55 advance is not sufficient materially to slacken the loops of yarn α detained by the advanced cylinder needles. The cylinder needles moving in their advanced position will now encounter the secondary yarn γ fed in any 60 suitable manner, as through a hole 10 in the portion 12 of the latch guard plate 3, and be withdrawn into their carrier to knit by the operation of a cylinder stitch-cam incline 34. The stitching movement of the 65 cylinder needles casts off both the yarn loop

of the cylinder face of the fabric and the detained sinker-wale loop of the dial fabric.

A preferred relation of the cylinder and dial knitting wave is such as that shown, by which the stitching movement of the secondary needles takes place during the retraction incident to the previous stitching movement of the primary needles, the sinker-wale loops of the dial or primary fabric thus being held strongly against the shanks of the secondary needles at a limited segment 70 of the secondary needles only, thus securing closure of the secondary needle latches and preventing taking into the hooks of the secondary needles the yarn of the primary 80 fabric, but without maintaining any great number of the tying or sinker-wale loops simultaneously under tension.

It will be observed that by my new devices coaction of the two sets of needles to knit two distinct fabrics closely connected together is secured within a relatively narrow angular segment of the two sets of needles. I may thus provide for multiple-course production as many sets of cams and 90 separate yarn feeds for their yarns as may be desired, my new device permitting a large number of such units to be crowded around the periphery of the machine.

While I have illustrated my invention in 95 connection with a latch needle machine, it will be obvious that the principles thereof are independent of the nature of the knitting instruments and that independently movable spring needles might be employed 100 in a corresponding manner, with suitable change in their coöperating instruments, such as will be obvious to those skilled in the art.

It will also be apparent that the cylinder 105 needles may be those first retracted, the dial needles remaining advanced, the position of the respective yarn guides being suitably changed to permit feeding the cylinder needles in advance of the dial 110 needles, and the relation of the cylinder and dial cams being changed to secure the retraction of the cylinder needles before the retraction of the dial needles.

What I claim is:

1. A knitting machine having a primary and a secondary set of needles, cams and a latch guard for maintaining said secondary needles in a state of advance with their latches open coincident with cams for advancing said primary needles, and having cams for retracting said primary needles to knit at a place defined by secondary needles remaining so advanced, and cams for retracting the secondary needles to knit immediately following said primary knitting cams, in combination with means for supplying separate yarns to the needles of the respective sets.

2. A knitting machine having in combina- 130

- tion a primary and a secondary set of latch needles, means for advancing said needles, a latch-guard device for holding open the latches of the needles of each set, means for 5 feeding a yarn into hooks of said primary needles held open by said latch guard device, means for retracting said primary needles to knit during maintenance of the advance of said secondary needles, means for feeding 10 another yarn to the open hooks of said secondary needles, and means for retracting said secondary needles to knit.
3. A knitting machine having in combination a primary and a secondary set of intermeshing latch needles, means for advancing and maintaining said primary and secondary needles in a state of advance, a latch guard surface for said advanced primary needles, means for retracting said primary 15 needles to knit at the end of said latch guard surface, a latch guard surface for holding open the advanced secondary needles, and means for retracting said secondary needles to knit operating after said 20 primary needles have been retracted to knit, and means for supplying separate yarns to the retracting needles of the respective sets.
4. A knitting machine for knitting connected plain fabrics having two sets of latch needles arranged to intermesh, a latch-guard device having surfaces for holding the latches of each set open, said surfaces terminating at separated points, in combination with guides for feeding independent yarns 25 to the needles of each set respectively at or near the termination of said surfaces, cams for advancing the needles into relation with 30 said surfaces and said yarn guides, and cams for retracting the needles of each set separately, each upon receiving its yarn. 40
5. A knitting machine having a cylinder and dial and sets of latch needles respectively therein in combination with a latch-guard device having a member providing surfaces above the dial needles to guard the 45 latches of each of said sets of needles when projected coincidentally, means to project the needles and spaced yarn feed guides for delivering independent yarns one after the other at said latch-guard device, one of said 50 latch-guarding surfaces being cut away at and beyond the yarn guide first to deliver its yarn, to permit closure of latches of the needles of one set, said machine having means for retracting the needles of said set 55 prior to actuation of the needles of the other set.
6. A knitting machine having two sets of latch needles and a latch-guard device therefor having a part with a guard surface for one set of needles of an extent and in a position to coincide with the crest of a relatively long wave of advance in said set of needles, said device having coincident with a part 60 only of said surface a second latch-guard surface for the needles of the other set, said device also having formed therein a latch-swinging opening for the needles of said other set lying within the area defined by 65 70 said wave of advance.

In testimony whereof I have signed my name to this specification.

LORAINE J. QUINN.
